Chas. E. Goss

UNITED STATES PATENT OFFICE.

FRANK A. WEEKS, OF PLAINFIELD, NEW JERSEY.

INKSTAND.

1,186,633.

Specification of Letters Patent. Patented June 13, 1916.

Application filed December 27, 1909. Serial No. 535,085.

To all whom it may concern:

Be it known that I, FRANK A. WEEKS, a citizen of the United States, and a resident of Plainfield, in the county of Union and 5 State of New Jersey, have invented certain new and useful Improvements in Inkstands, of which the following is a specification.

The invention relates to improvements in inkstands, and its object is to provide a 10 highly desirable and convenient inkstand comprising a novel base containing, preferably, two or more ink-wells, and a loose rotary removable cover applied over said wells and having a dip-opening which on the rotary movement of the cover may be carried over either of said wells, said dip-opening during the non-use of the inkstand being over a solid portion thereof which closes said opening and by being slightly convexed upwardly to enter the opening operates to hold the cover stationary concealing both or all the ink-wells.

The invention consists in the novel features hereinafter described and claimed and 25 will be understood from the following description, reference being had to the accompanying drawings, in which:

Figure 1 is a perspective view of an inkstand embodying my invention, the cover 30 being shown in closed position or concealing the ink-wells and with the dip-opening in the cover closed at its lower end; Fig. 2 is a central vertical longitudinal section of the same, on the dotted line 2—2 of Fig. 4; Fig. 3 is a vertical transverse section of the same, 35 on the dotted line 3—3 of Fig. 4; and Fig. 4 is a top view of the base of the inkstand, the cover being omitted.

In the drawings, 10 designates the glass 40 base of the stand and 11 the rotary cover therefor. The base 10 may be formed with a front pen-rack 12 and contains two substantially semi-circular side by side ink-wells 13 for use in holding different inks. Red 45 ink may be placed in one well 13 and black ink in another well. The ink-wells are separated by an integral partition 14 extending centrally from front to rear and merging at its front end into a widened portion or table 50 15 which bears a slightly upwardly convexed hump or projection 16. Extending around the wells 13 is a circular encompassing raised flange 17, outside of which the sur-

face of the base 10 is preferably flat. The base 10 is a low rectangular glass-block of 55 considerable area beyond the wells 13 and when placed on a desk or table is not liable under any usual conditions to be upset.

The cover 11 will preferably be formed of composition and it is in the general form of 60 a disk having a convexed upper side and a depending encompassing flange 18 which fits loosely around and embraces the flange 17 on the base 10, as shown in Figs. 2 and 3. The cover 11 is formed at one side of its 65 center with a dip-opening 19 which, by the rotation of the cover, may be located or moved over either well 13 to admit a pen thereto. The dip-opening 19 may also be moved over the table 15 when the inkstand 70 is not in use so that the cover may fully conceal both wells 13, and for yieldingly retaining the cover in its well-concealing or closed position I provide on the table 15 the convex projection 16 over which the cover 75 may ride and around which the dip-opening 19 will settle when said opening reaches the same. The projection 16 serves as a guide to the user in closing the inkstand and by extending upwardly into the opening 19 arrests the cover in its proper closed position 80 and yieldingly there retains it. I regard it as important that the base be provided with the upwardly extending flange 17 to receive and be encompassed by the depending flange 85 18 on the cover. The cover 11 is entirely free to be lifted off from the base at any time and it is also capable of free rotation on said base, the fit of the flange 18 on the flange 17 being a loose one.

What I claim as my invention and desire to secure by Letters Patent, is:

A two-part inkstand comprising an integral rectangular glass base formed well within its vertical edges with two substantially semi-circular side-by-side open-top ink-wells separated from each other by a partition integral with the base extending centrally from front to rear and a front table portion set inwardly within the circle 95 defined by said wells and into which the front end of said partition merges, and with a raised circular flange integral with the base and extending around said wells, table portion and the rear end of said partition, 100 said base being extended outwardly beyond 105

said flange and affording a flat top, and a circular rotary disk cover having a dip-opening and a depending surrounding flange fitting loosely over the said circular flange and freely removable therefrom, said dip-opening being located to, on the rotation of the cover, rest over said table portion or over either of said wells, as shown and described.

Signed at New York city, in the county of New York, and State of New York, this 10
22nd day of December A. D. 1909.

FRANK A. WEEKS.
